UNITED STATES PATENT OFFICE.

BENJAMIN K. VERBRYCK AND THOMAS NEWBERRY, OF CHICAGO, ILL.

IMPROVEMENT IN CAR-AXLE BOXES.

Specification forming part of Letters Patent No. 159,622, dated February 9, 1875; application filed January 18, 1875.

To all whom it may concern:

Be it known that we, BENJAMIN K. VERBRYCK and THOMAS NEWBERRY, of Chicago, in the county of Cook and State of Illinois, have invented a new and Improved Car-Axle Box, of which the following is a specification:

In the accompanying drawing, Figure 1 represents a side view, and Fig. 2 a front view, of a car-axle box with our improved cover or lid fastening latch. Fig. 3 is a rear view of the eccentric latch detached, and Fig. 4 an end view of the cover or lid, with the groove and cam for the attaching of the latch-piece.

Similar letters of reference indicate corresponding parts.

The object of our invention is to improve the axle-boxes of railway-cars in such a manner that the covers or lids are locked or fastened in an absolutely secure manner without the use of set-screws, springs, or other devices which are liable to get lost or out of order.

Our invention consists of a cover or lid which is hinged to one side of the axle-box, and provided at the other side with a groove and cam, into which a pivoted latch-piece with eccentric cam is swung for locking rigidly the cover.

In the drawing, A represents a car-axle box of any of the usual constructions; B, the cover or lid, which is hinged to one side and fitted to close tightly over the opening of the box. The free side of cover B is about centrally provided with a groove or recess, a, concentric to the pivot of the locking latch-piece B' at the side of the axle-box. The groove a encircles a flat segmental cam-piece, b, which, at its lower corner, is slightly cut off or inclined, as indicated in Fig. 4, for the purpose of passing along the slightly-curved cam part d of the latch B', when the same is carried too far back in open position, so as to bring it thereby forward by the pressure of the lid in clos-

ing, and set it into exact position for being turned down. The latch-piece B' has a crank or lever handle, and is recessed at its lower or rear side in such a manner that a part of its circumference is open for the entrance of the cam b of the lid, while an eccentrically-tapering cam, e, is formed along the circumference and terminated in the curved radial cam part d. The end of the eccentric cam part e enters the groove a of the lid on being swung down, and slides along the cam-piece of the same till the eccentricity of the cam binds gradually tighter and tighter on the cam of the lid, and locks the same finally rigidly to the box without a possibility of its playing loose until thrown up again for opening the lid in refilling the oil-box. The lid-fastening is extremely simple, being opened and closed with the greatest facility, and is thereby less liable to get out of order than the common set-screw, spring, or other locking devices hitherto employed.

Having thus described our invention, what we claim as new, and desire to secure by Letters Patent, is—

1. The combination of hinged lid B, having side groove a, and cam b, axle-box and pivoted latch-piece B', having on its recessed lower side a snail-cam for locking the lid, substantially in the manner and for the purpose set forth.

2. The segment cam-piece b of the lid, having its lower corner obliquely cut away, in combination with the radial cam end d of the latch, for causing the same to lock on closing the lid, substantially as set forth.

BENJAMIN KERBY VERBRYCK.
THOMAS NEWBERRY.
